(57) **CLAIM**

The ornamental design for a firearm holster as shown and described.

DESCRIPTION

FIG. 1 is a front, top left perspective view of a firearm holster in accordance with the present invention.

FIG. 2 is a front, top right perspective view of the firearm holster.

FIG. 3 is a rear, top left perspective view of the firearm holster.

FIG. 4 is a rear, top right perspective view of the holster.

FIG. 5 is a front view of the firearm holster.

FIG. 6 is a rear view of the firearm holster.

FIG. 7 is a top view of the firearm holster.

FIG. 8 is a bottom view of the firearm holster.

FIG. 9 is a left view of the firearm holster.

FIG. 10 is a right view of the firearm holster; and,

FIG. 11 is a front view of the firearm holster.

The broken line portions of the drawings represent environmental structure of the firearm holster and form no part of the claimed design.

1 Claim, 6 Drawing Sheets
